FOUNTAIN PEN

Louis Chayka, Detroit, Mich.

Application July 20, 1935, Serial No. 32,463

6 Claims. (Cl. 120—46)

My invention pertains to improvements in fountain pens and particularly in filling means for fountain pens using transparent barrels. There is already a number of such pens on the market but the majority of them have certain disadvantages and faults. Some of them are too complicated and difficult to manufacture, some are likely to develop leaks, and others can be filled with ink only gradually by repeated operations.

It is agreed that the best pen at present is the common variety using a rubber sack, except for the fact that the pen does not show the quantity of ink therein. The purpose of my invention, therefore, is to combine the best qualities of the ordinary sack pen with the advantages of the pen employing a transparent barrel showing the level of ink therein. More specifically, my object is to provide:—

- 1st. A pen that has a transparent barrel and uses an improved filling device.
- 2nd. A filling device that is simple in construction and operation.
- 3rd. A filling device that may be removed from the barrel as a unit.
- 4th. A filling device that will fill the pen with one stroke of a pushbutton or one turn of a knob.
- 5th. A filling device that will not be likely to get out of order.
- 6th. A filling device that will draw into the barrel a large quantity of ink.
- 7th. A filling device that may be wedged into the barrel without the need of any cement.
- 8th. A filling device that will be durable, economical, easily manufactured and easily assembled.

I accomplished all these purposes by novel means, namely, by using in the barrel of the pen a rubber sack or a rubber tube closed at one end, not as an ink reservoir but as a means of varying the ink carrying capacity of the barrel. Ink in my pen is not in the sack but outside the sack or tube, that is, it is contained between the outer wall of the sack and the inner wall of the barrel. The only outlet from the barrel is through the ink feeding groove on the feeding bar supplying ink to the pen-point, so, when I expand the sack, I expel the ink from the barrel. When the sack is collapsed, the resulting vacuum in the barrel draws in ink thereinto.

My invention exists, not only in the construction, arrangement and combination of the various parts, whereby the objects contemplated are obtained by them, but especially in the broader idea of expanding or collapsing the rubber sack mechanically for the purpose of expelling or

drawing in ink contained in the barrel outside of the sack as set above. Once this principle has been disclosed, it will be quite possible to devise a number of different structures to carry out the idea without materially departing from my original conception as disclosed.

Selecting a fountain pen incorporating the preferred construction of my filling device, I will explain it by reference to the accompanying drawing, in which

Fig. 1 presents a longitudinal section of the pen.

Fig. 2 presents a section across the barrel on line 2—2.

Fig. 3 presents a longitudinal section of a different species of a pen employing a pushbutton.

Fig. 4 presents a section across the barrel of the pen on line 4—4.

Fig. 5 presents a magnified illustration of a detail of the pen shown in Fig. 3.

The pen, as shown in Fig. 1, comprises a barrel 10, into the lower end of which is secured the usual section 11 with a feed bar 12, groove 13 and a pen-point 14, arranged in the customary manner, except that the feed bar may project somewhat into the barrel as shown.

The upper end of the barrel is closed with a plug 15 drilled centrally, said plug being of a slightly smaller diameter in its lower half to accommodate the upper end of the rubber sack 16, which is 30 tightly wedged between the plug and the inside wall of the barrel 10. The sack is wedged in such a manner that neither air nor liquid may pass from or into the barrel at any point around the plug. Quite obviously, the upper end of the sack 35 may be cemented to the lower end of the plug without being wedged as above stated or it may be otherwise secured to the plug and the plug cemented or threaded into the end of the barrel.

The rubber sack 16, extending substantially the full length of the barrel, is closed at its lower end. It is of a diameter large enough to occupy practically the whole space of the barrel when fully expanded. Normally, however, the sack is collapsed, as shown in Fig. 2, occupying in its collapsed state but a small space of the inside of the barrel. Firmly, attached to one side of the plug 15 is a thin rigid shell 17, arcuate in shape, parallel to the inside surface of the wall of the barrel and extending in a close proximity of said wall straight down within a short distance of the feeding bar 12. At this point, it narrows and turns at the right angle towards the center of the barrel, in the form of a straight arm 18, 50 55

above said feeding bar. At its end above the said feeding bar, the arm 18 is provided with a socket 19.

5 Rotatably journalled in the center of the plug 15 is a short shaft 20. Its upper end, outside of the barrel, ends with a knob 21. Its lower end is within the barrel and is joined to a short arm 22, disposed at the right angle to the shaft and extending into another arcuate shell 23, running 10 at right angle to the arm 22 and in a direction parallel to the short shaft 20. At its lower end, the shell turns again at right angle, to the center of the barrel, and terminates in a transverse lug 24 rotatably supported in socket 19.

15 Normally, the movable shell 23 nestles in the concave recess formed by the curved surface of the stationary shell 17. When the shells are in this position, they occupy as little space as possible. When rotated by means of the knob 21, in 20 either direction, the movable shell is capable of describing a complete circle. Both shells are enclosed by the aforementioned rubber sack 16 and rest upon the upper end of the feeding bar 12 to add stability to the shells. 25 is a cap provided with a thread on the inside lower surface and fits over the correspondingly threaded upper part of the plug 15.

Referring to Fig. 2, numeral 10 shows the wall of the barrel; the rubber sack 16 is collapsed, 30 with the two shells, the stationary 17 and movable 23, in a normal, before-operative position. The dotted outline 16'' shows the position of the sack when it is expanded, while the dotted outline 23'' shows the position of the movable shell 23 when the same has been turned 180 degrees from its normal position in order to expand the rubber sack 16. 34 and 34'' are beads at the edges of the shells to prevent them from interlocking.

35 40 In Fig. 3, I have illustrated a different construction of my pen, in which I am using a push-button at the top of the pen to cause the expansion of the rubber sack or tube.

In this figure, 10 is the wall of the barrel; parts 45 11, 12, 13, 14, 15 and 16 are the same as in Fig. 1. Sack 16 is of a diameter large enough to occupy practically the whole interior space when fully expanded.

Normally, however, it is collapsed into a flat-50 tened shape, as shown in Fig. 4, and occupies the central section of the barrel, as shown in said Fig. 4.

55 Slidably in the center of the plug 15 is located a short rod 20, the upper end of which outside the barrel, ends in a push-button 26. The lower end of the said rod is within the barrel and within the sack 16. Hinged to the lower end of the rod are two semi-circular leaves 27 and 28, so disposed with relation to each other that 60 when spread, they present the appearance of a disk. The semi-circular leaves are free to swing up and down from the hinge. This is shown in Fig. 5. Hinged to the lower ends of the semi-circular leaves 27 and 28, are stiff strips 29 and 65 30, preferably made of metal and extending down within a small distance from the bottom of the barrel where the strips are joined to a similar pair of semi-circular leaves 31 and 32, except that the leaves point upward from their hinge at 33.

70 The purpose of these semi-circular leaves is to expand the sack into a round tube that it may occupy as much space as possible. To that end additional pairs of leaves between the two pairs

already mentioned might be introduced if found desirable.

Normally, the rubber sack being collapsed and under the pressure from the said normally collapsed rubber sack, the leaves, both the upper 5 ones and the lower ones, are folded together as shown in dotted outline 27'' and 28'', also 31'' and 32''. The strips, also brought together by the position of the leaves and the pressure of the sack, occupy positions 29'' and 30''. 10

The rubber sack, secured in an air and water-tight manner at the top of the barrel between the plug 15 and the inner surface of the barrel, envelopes all said leaves and side strips and, as before stated, is in a collapsed position 16''. 15

Fig. 4 shows a section of the pen across the barrel on line 4-4, 10 being the wall of the barrel, 16 the sack, 29 and 30 the side strips when brought together as stated above.

Fig. 5 shows the detailed construction of the 20 upper leaves 27 and 28 with the pushrod 20 attached to the hinge supporting the leaves. Strips 29 and 30 are presented fractionally.

The following is the manner in which the pen shown in Fig. 1 may be filled with ink: The barrel 25 being empty and the rubber sack 16 being in its normal collapsed state, I turn the knob 20 completely around. In doing so, I first bring the arcuate movable shell 23 diametrically in opposition to the stationary arcuate shell 17 as shown 30 in Fig. 2, where it is presented to occupy position 23''. As a result the rubber sack 16 is expanded fully and most of the air contained in the barrel is expelled. When, however, the rotation of the movable shell 23 continues, and the shell on completion of the full 360 degrees turn, assumes the original position within the stationary shell 17, the rubber sack collapses again to its original shape and the partial vacuum resulting therefrom in the barrel causes ink to be drawn into 40 the barrel.

To expel ink from the barrel all that is necessary is to again turn the knob around its axis, which as stated above, will through the instrumentality of the arcuate shells, expand the sack 45 and cause the ink to flow out from the barrel.

The barrel of the pen shown in Fig. 3 is filled by depressing down the push button 20.

When the rod is depressed it causes the semi-circular leaves and strips hinged thereto to spread 50 apart and to expand the sack 16. The expansion of the sack expels most of the air from the barrel. When the pressure from the pushrod is removed, the leaves and the strips come together under the pressure of the enveloping rubber sack 55 16, the sack assumes its original collapsed position as shown in Fig. 4, and the difference between the capacity of the expanded sack and that of the collapsed sack, results in a partial vacuum 60 in the barrel, which vacuum causes ink to be drawn into the barrel. To expel ink, all that is necessary is to press again the button 26 on the top of the pushrod 20.

There is a number of other constructions that 65 suggest themselves for the same purpose of mechanically expanding the sack and they can be easily designed by anyone endowed with ordinary mechanical skill. The above described constructions are only samples of what can be done and it is plain that other designs of the same nature are possible and may be made without departing from the principle of my disclosures. I, therefore, wish my invention to embrace all such changes, variations, and modifications as will nat- 70 75

urally suggest themselves to persons skilled in the fountain pen art.

What I claim is:

1. A fountain pen comprising an ink carrying barrel a grooved feeding bar and a penpoint set at one end thereof, a normally collapsed expandable sack open at one end, set at the other end of the barrel and extending substantially the whole length of the barrel, tangible mechanical means within said sack, operable from without to cause the sack to expand to occupy substantially the whole space of the barrel and in turn to cause the said sack to collapse to its original shape.
- 15 2. In a fountain pen of the kind described, filling means comprising an expandible, normally collapsed sack, set at one end of the barrel and extending substantially the whole length thereof, the said sack being closed at the lower end and open at its upper end, two elongated arcuate shells, pivotally joined at both ends, placed within the said sack and one of said shells being capable of being moved with relation to the other so as to be placed diametrically in opposition to the other or closely within the other and means to operate said movable shell.
- 20 3. In a fountain pen of the kind described, an expandible sack normally collapsed, placed within the barrel of the pen and extending substantially the whole length of the barrel, and means to expand said sack consisting of a stationary elongated

member placed within the sack close to its wall and a similar movable member also within the sack to bear against the opposite wall of same when manually actuated by means outside the sack.

5 4. In a fountain pen of the kind described, filling means consisting of an expandible sack set at one end of the barrel and means to expand said sack comprising a pushrod, placed slidably in the plug closing the mouth of the sack, a 10 pair of spreadable semi-circular leaves placed within the sack and directly beneath the pushrod, and at least another pair of similar leaves at the lower end of the sack, a pair of strips hingedly connecting the said pairs of leaves, said leaves 15 being normally in a collapsed folded position, but being capable of being spread under the action of the said pushrod.

5 5. In a fountain pen comprising a barrel, a feeding bar and a penpoint set at one end thereof, a normally collapsed expandible sack open at one end, set at the other end of the barrel and extending the whole length of same, a plurality of elongated members placed within the sack and means to spread apart said members to bear 20 against and to expand the walls of the said sack.

6. In a fountain pen a barrel, a normally collapsed sack therein and means within the sack bearing against the walls thereof, operable from without, to expand same.

30 LOUIS CHAYKA.
